UNITED STATES PATENT OFFICE.

JAMES G. McNAMARA, OF BROOKLYN, NEW YORK, ASSIGNOR TO MERGENTHALER LINOTYPE COMPANY, A CORPORATION OF NEW YORK.

TYPOGRAPHICAL MACHINE.

Application filed May 9, 1925, Serial No. 29,027. Renewed June 15, 1927.

My invention relates to typographical machines, such as linotype machines of the general organization represented in Letters Patent of the United States to O. Mergenthaler No. 436,532, wherein circulating matrices are released from a magazine in the order in which their characters are to appear in print and then assembled in line, the composed line transferred to the face 19 of a slotted mold, the mold filled with molten metal to form a slug or linotype against the matrices which produce the type characters thereon, and the matrices thereafter returned through distributing mechanism to the magazine from which they started. More particularly, it relates to that 25 class of machines capable of handling both ordinary and display fonts, such as that shown and described in the Kennedy Patent No. 1,897,974, wherein the keyboard connections may be adjusted at the will of the operator to provide for the release of matrices of one kind or another, as desired, notwithstanding their different location in their 30 respective magazines.

The present invention contemplates an improved arrangement for accomplishing somewhat the same results. It is herein proposed to employ two sets of escapement actuating rods which may be adjusted to bring one set or the other into operative relation to the keyboard, as desired. The rods of one set are operable independently to actuate the escapements of a magazine containing an ordinary font, while those of the other set are arranged to actuate the escapements of a magazine containing a display font through certain rods of the first set. To be more specific, the rods of the second 40 set have their lower ends aligned with the rods of the first set so as to be operated by the same finger keys, but have the upper ends of some offset laterally to engage and operate different rods of the first set in actuating the escapements of the display magazine. The adjustment of the escapement actuating rods is controlled in such manner that when either a display or an ordinary 45 font is brought into use, the finger keys will be caused to effect the release of the corresponding matrices without regard to their different relative location in the magazine channels.

In the accompanying drawings, I have 50 shown my improvements in connection with

magazines of different widths and as applied to a shiftable multiple magazine machine of the kind known to the trade as "model 8," or such as is illustrated in the Rogers Patent No. 1,109,872, but it should be understood that they are equally applicable to magazines of the same or standard size as well as to machines of other kinds, including those equipped only with a single magazine. In short, I have herein shown my invention merely in preferred form and by way of example, and obviously many changes and modifications may be made therein without departing from its spirit. I therefore desire it to be understood that I do not limit myself to any specific form or embodiment, except in so far as such limitations are specified in the claims.

Referring to the drawings:

Fig. 1 is a front elevation of a linotype machine embodying the present improvements;

Fig. 2 is a side elevation on an enlarged scale of the parts shown in Fig. 1;

Fig. 3 is a front elevation of the left-hand portion of the assembling mechanism with the front plate removed; and

Fig. 4 is a transverse, vertical section, showing the improved connections between the keyboard mechanism and a magazine.

As in the Rogers patent before mentioned the several magazines are carried by the shift frame A, composed in part of the two swinging base frames A¹, and which is arranged to be raised and lowered in the well-known manner by the operation of a hand crank so as to bring any selected one of the magazines into operative relation to the assembler entrance B. The magazines are located in operative position by the ordinary locking bar C, which is slidably mounted in the fixed brackets C¹ and controlled from the rock shaft C² through the intermediate connecting arms C³. The bar C, as usual, is normally held in its locking position by a spring C⁴ and is moved manually to unlocking position by means arranged within convenient reach of the operator, such means in the present instance comprising the offset lever C⁵ fastened at its rear end to the shaft C² and provided near its forward end with a notch C⁶ presenting shoulders C⁷, the purpose of which will hereinafter be pointed out. As shown, the shift frame A is provided with two magazines V and with a sin-

gle magazine Z, the magazines Y being of the regular or standard form and provided with ninety-one grooved channels spaced apart in the usual way to adapt them to contain the ordinary ninety character matrix fonts, whereas the magazine Z, although similarly provided with ninety-one grooved channels, is of special form, being wider than the magazines Y and having its channels more widely spaced apart to adapt them to contain a ninety character matrix display font. The magazines Y and Z are provided with series of escapements Y¹ and Z¹, respectively, which control the release of the individual matrices, and these escapements or those of the operative magazine are adapted to be actuated by a single row or series of power-operated slides D¹ (ninety in number) controlled from the finger keys of the keyboard D through the usual trip dogs D², cam yokes D³, and constantly driven rolls D⁴.

Ordinarily, a single set of rods or reeds having their lower ends arranged in operative relation to the cam yokes is employed to actuate the magazine escapements, either directly or through a corresponding set of escapement levers. However, in the present instance, since like matrices of the ordinary and display fonts are controlled by escapements located respectively in different vertical planes, means are provided for establishing one series of connections between the finger keys of the keyboard and the escapements of a regular magazine when the common position of straight matter is desired, and another series of connections between the keys and the escapements of the special magazine when the larger or display matrices are desired. In the embodiment illustrated, there are employed two sets of escapement actuating rods E, E¹, mounted in a pivoted frame F, which may be adjusted to and fro to bring either set into operative relation to the key-controlled slides D¹. The rods E are substantially uniform in shape and length throughout and afford a series of direct connections between the slides D¹ and the escapements of a regular magazine Y when in operative position. The rods E¹, on the other hand, which are employed in making up the other series of connections or those for the wide magazine Z, while having their lower ends aligned respectively with the rods E so as to be actuated by the same slides D¹, are of different lengths, the longer ones (those comprising the two groups located at the extreme right and left, Fig. 1), affording, like the rods E, direct connections between the slides D¹ and such escapements of the wide magazine as are located beyond the lateral limits of the regular magazines, and the shorter rods (those arranged between the two side groups) being offset at their upper ends so as to engage and operate certain of the rods E in

actuating such escapements of the wide magazine as are located within the lateral limits of the regular magazines. In other words, some of the escapements of the wide magazine are disposed in the same vertical planes as certain escapements of the regular magazines, and hence the offsetting of the shorter rods E¹ is carried out in such manner that, in actuating the appropriate escapements of the wide magazine when the latter is in use, they will operate those rods E of the first set which actuate the correspondingly located escapements of the regular magazines. To do this, the upper offset ends of the shorter rods E¹ are made to engage in notches formed in the rear edges of the appropriate rods E. With the arrangement just described, when one of the regular magazines Y is brought into use, the frame F is adjusted to locate the rods E in operative relation to the slides D¹, so that the finger keys will be properly connected to the escapements of the selected magazine for the release of corresponding matrices of the ordinary font therein contained; whereas, when the special magazine Z is selected for use, the frame F is adjusted to bring the rods E¹ into operative relation to the slides D¹, so that the finger keys will be properly connected to the escapements of that magazine for the release of the corresponding matrices of the contained display font.

As a further feature of the invention, it is proposed to provide means whereby the two said series of connections above described are established automatically, and preferably so that when a regular magazine is substituted for the display magazine, or vice versa, the corresponding set of escapement actuating rods will be properly connected to the keyboard by the same act. To this end, there is provided a lever G pivoted between its ends to a stationary bracket G¹, located at the extreme left-hand side of the entrance B. The lower end of the lever G is arranged to engage an upwardly disposed arm F¹ on the shift frame F, while its upper end is located in the path of the wide or display magazine Z so as to be engaged thereby when the latter is brought into use. When the lever G is thus engaged with the magazine Z, the shift frame F will be set with the rods E¹ in operative relation to the slides D¹, it being remembered that such rods are the ones employed to control the release of the display matrices. A pull spring F² arranged between the arm F¹ and the assembler front plate O serves to hold said parts in their adjusted position. When one of the regular magazines is brought into use, however, the lever G (as shown in the drawings) is arrested by a pin J¹ protruding from a pivoted yoke or frame J, presently to be described. This pin J¹ serves to set the shift frame with the actuating rods E in

operative relation to the slides D¹ (see Fig. 2). Instead of having the frame F shifted to its adjusted positions during the actual movement of the magazines, as might well be the case, it is proposed to rock the control lever G out of the path of the magazines as the locking rod C is released, such rod, as before stated, being employed to locate the respective magazines in operative position. By this action, the frame F is shifted forwardly to an abnormal position, and as the rod C is returned to its locking position by the spring C⁴, the upper end of the lever G will be allowed to seat against the end of the display magazine if the latter happens to be the one selected, or remain seated against the stop pin J¹ if one of the regular magazines is selected.

In order that the escapement rods E, E¹ may be moved out of the path of the magazines during their interchange, they are guided at their upper ends in an angle plate J² secured to the yoke J, the latter being pivotally mounted on the rod J³ and arranged so as to be rocked back and forth by the hand lever C⁵, before referred to. Connection between the yoke J and the hand lever C⁵ is effected by a short arm J⁴ extending forwardly from the yoke J and having a stud J⁵ arranged to engage the shoulders C⁷, C⁸ of the notch C⁶ formed in the crotch of the lever C⁵. An adjustable stop pin J⁶, carried in the end of an arm J⁵ extending rearwardly from the yoke J and engaging the supporting bracket O¹, is held against the latter by the spring C⁴ through the lever C⁵ and serves to locate the upper ends of the rods E, E¹ in operative relation to the magazine escapements. It will now be clear (see Fig. 2) that, by depressing the hand lever C⁵ to unlock the magazines, the shoulder C⁷ will engage the stud J⁵ and rock the upper ends of the rods E, E¹ from under the escapements and out of the way of the magazines. At the same time, the pin J¹, against which the lever G is held by the spring F², rocks the upper portion of said lever forwardly through the arm F¹ and shifts the frame F so as to carry the lower ends of the escapement actuating rods to an abnormal position forward of the slides D¹. The parts are maintained in this condition until the selected magazine is brought into operative position, when the hand lever C⁵ is released and the parts allowed to resume their normal condition, as indicated. However, if the magazine selected happens to be the wider or display magazine Z, the upper end of the lever G will be arrested thereby as the frame J moves backwardly and sets the frame F with the rods E¹ in operative relation to the key-controlled slides D¹ of the keyboard, as required.

It is pointed out that while the invention includes means for assembling matrices from

magazines of different widths, the improvements herein shown and described are equally applicable to magazines of the same width and like form, except in so far as the automatic selection of the actuating rods is concerned, and this latter feature could be readily retained by providing the magazines with distinguishing projections of some sort arranged to cooperate with the control lever G. Thus, for example, the present scheme for establishing operative connections between the keyboard and two fonts of matrices, wherein like matrices are disposed in different relative vertical planes, would apply just as well where the ordinary ninety channel magazine was combined with the commercial seventy-two channel display magazine. Of course, in such event, the changes incurred by widening the assembler entrance (as shown in Fig. 1) would not be necessary and the groups of longer rods E¹ at the left and right could be eliminated. These and other modifications will readily suggest themselves to those skilled in the art and still be comprised within the scope of the invention.

Having thus described my invention, its construction and mode of operation, what I claim and desire to secure by Letters Patent of the United States, is as follows:

1. In a typographical machine, the combination of two interchangeable magazines of different widths, one containing a font of matrices occupying certain channels according to character, and the other containing a font of matrices occupying differently located channels according to character, means for selecting either magazine for use, a keyboard, two sets of escapement actuating rods through which the finger keys of the keyboard control the release of like matrices of the two fonts, and means for connecting the rods of either set to the respective finger keys according to the magazine selected.

2. In a typographical machine, the combination of two interchangeable magazines of different widths, one containing a font of matrices occupying certain channels according to character, and the other containing a font of matrices occupying differently located channels according to character, means for selecting either magazine for use, a keyboard, two sets of escapement actuating rods through which the finger keys of the keyboard control the release of like matrices of the two fonts, and means operable by said selecting means for connecting the rods of either set to the respective finger keys according to the magazine in use.

3. In a typographical machine, the combination of two magazines of different widths and each provided with a series of escapements, some of the escapements of the wider magazine being arranged in the same vertical planes as certain escapements

of the other magazine, a keyboard, and two sets of escapement actuating rods, those of one set being operable independently by the finger keys to actuate the escapements 5 of one magazine, and those of the other set being operable by the same respective finger keys but having their upper ends offset laterally to actuate directly certain escapements of the wider magazine and others indirectly 10 through such rods of the first set that actuate the escapements vertically aligned with those of said wider magazine.

4. In a typographical machine adapted to be equipped with interchangeable magazines, one containing a font of matrices occupying certain channels according to character, and the other containing a font of matrices occupying differently located channels according to character, the combination 20 of a keyboard, and two sets of actuating rods through which the finger keys of said keyboard control the release of like matrices of the two fonts, the rods of one set being operable independently to release the matrices of one font, and those of the other set being arranged to operate, at least in part, through certain rods of the first set to release the matrices of the other font.

5. In a typographical machine, the combination of two interchangeable magazines provided with differently spaced escapements, some of the escapements of one magazine being arranged in the same vertical 35 planes as certain escapements of the other magazine, means for selecting either magazine for use, and two sets of key-controlled escapement actuating rods, those of one set being arranged to actuate directly the respective escapements of one magazine, and 40 those of the other set being arranged to actuate the escapements of the other magazine, at least in part, through such rods of the first set that actuate the correspondingly located escapements of the first magazine.

6. In a typographical machine, the combination of two interchangeable magazines, each provided with a series of escapements, those of one magazine being spaced apart 50 differently from those of the other magazine, means for selecting either magazine for use, a single series of finger keys, two sets of escapement actuating rods, an adjustable frame wherein both sets are mounted, and means controlled by the magazine selected for automatically adjusting said frame to bring the corresponding set of actuating rods into operative relation to said finger keys.

60 7. In a typographical machine, the combination of two interchangeable magazines provided with differently spaced escapements, some of the escapements of one magazine being arranged in the same vertical 65 planes as certain escapements of the other

magazine, means for selecting either magazine for use, a series of finger keys, and two sets of escapement actuating rods adjustably arranged so that one set or the other may be brought into operative relation to said 70 keys, the rods of one set being operable independently to actuate the escapements of one magazine, and those of the other set having their upper ends offset laterally to actuate the escapements of the other magazine, at least in part, through such rods of the first set that actuate the corresponding- 75 ly located escapements of the first magazine.

8. In a typographical machine adapted to be equipped with interchangeable magazines, each provided with a series of escapements, the escapements of one magazine being spaced apart differently from those of the other magazine, a single series of key-controlled power-operated devices, two sets of escapement actuating rods, those of one set being operable independently to actuate the escapements of one magazine, and those of the other set being arranged to operate, at least in part, through certain rods of the first set in actuating the escapements of the other magazine, an adjustable frame wherein the rods of both sets are mounted, and means controlled by the magazine in use for locating the adjustable frame with the corresponding set of actuating rods in operative relation to said key-controlled devices.

9. In a typographical machine, the combination of two interchangeable magazines, each provided with a series of escapements, those of one magazine being spaced apart differently from those of the other magazine, means for selecting either magazine for use, a series of finger keys, two sets of intermediate escapement actuating rods, one set being operable in conjunction with the other to actuate the escapements of one magazine, and the other set being operable independently to actuate the escapements of the other magazine, and means for bringing either set under the control of the finger keys according to the magazine selected.

10. In a typographical machine, the combination of a keyboard and two sets of escapement actuating rods adjustably arranged so that either set may be operatively connected to the keyboard, the rods of one set being operable independently, and those of the other set being arranged to engage and operate certain selected rods of the first set, at least in part.

11. In a typographical machine, the combination of a keyboard, a single series of key-controlled power-operated devices, two sets of escapement actuating rods having their lower ends aligned so as to be operated by the same key-controlled devices, an adjustable frame in which both sets are mounted, and means for adjusting the frame 125 130

to bring either set into the range of action of said devices, the actuating rods of one set being arranged to function independently, and those of the other set being offset laterally at their upper ends to function, at least in part, through certain rods of the first set.

12. In a typographical machine, the combination of two interchangeable magazines, each provided with a series of escapements, the escapements of one magazine being spaced apart differently from those of the other, means for selecting either magazine for use, a series of finger keys, two sets of escapement actuating rods, one for each magazine, an adjustable frame wherein the lower ends of said rods are mounted, a pivoted yoke for moving the rods out of the path of the magazines, an intermediate lever connected to said frame and having its upper end arranged to cooperate with one of said magazines to locate the corresponding set of escapement rods in operative relation to the finger keys, and a stop member carried by the yoke and arranged to engage said lever for similarly locating the set of escapement rods for the other magazine in operative relation to the finger keys.

13. In a typographical machine, the combination of two interchangeable magazines, each provided with a series of escapements, the escapements of one magazine being spaced apart differently from those of the other, means for selecting either magazine for use, manually controlled means for locking the selected magazine in position, a series of finger keys, two sets of escapement actuating rods, one for each magazine, an ad-

justable frame wherein the lower ends of said rods are mounted, a pivoted yoke for supporting the upper ends of the rods, an intermediate lever connected to both yoke and frame and controlled by the magazine in use to locate the corresponding set of escapement actuating rods in operative relation to the finger keys, and means whereby the operation of said locking means automatically rocks said yoke to swing the upper ends of the rods out of the path of the magazine and to permit the readjustment of said frame and escapement rods through said lever as determined by the magazine selected.

14. In a typographical machine, the combination of two interchangeable magazines, each provided with a series of escapements, the escapements of one magazine being spaced apart differently from those of the other, means for selecting either magazine for use, a device for locking the selected magazine in operative position, a hand lever for releasing said device, a series of finger keys, two sets of escapement actuating rods movably arranged so that either set may be brought into operative relation to the finger keys and escapements, means operable by the hand lever for shifting the rods of both sets out of operative relation to the finger keys and escapements as the locking device is released, and means controlled by the selected magazine for automatically bringing into operation the corresponding set of escapement rods as said locking device is restored to its locking position.

In testimony whereof, I have affixed my signature hereto.

JAMES G. McNAMARA.
